UNITED STATES PATENT OFFICE.

GEORGE McGOVERN, OF RICHMOND, VIRGINIA.

COMBINED KEY-HOLE GUARD AND CIGAR-CUTTER.

SPECIFICATION forming part of Letters Patent No. 318,275, dated May 19, 1885.

Application filed December 16, 1884. (No model.)

To all whom it may concern:

Be it known that I, GEORGE McGOVERN, a citizen of the United States, residing at Richmond, in the county of Henrico and State of Virginia, have invented certain new and useful Improvements in Combined Key-Hole Guards and Cigar-Cutters; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention has relation to combined key-hole guards and cigar-cutters; and the object of the device is to provide a simple and convenient tool of this class for smokers and travelers, which will be useful for clipping the ends 20 of cigars, and at the same time be serviceable as a key-hole guard; and to these ends the novelty consists in the construction, combination, and arrangement of the parts of the same, as will be hereinafter more fully described, and 25 particularly pointed out in the claims.

In the accompanying drawings the same letters of reference indicate similar parts of the invention.

Figure 1 is a perspective view of my invention. Fig. 2 is a similar view with the case separated so as to show the two interior levers; and Fig. 3 is a perspective view of a door-lock with the device inserted in the key-hole as a guard to prevent the insertion of a key 35 from the outside.

The casing of the device consists of two halves, A and B, preferably struck up of sheet metal, the half side B inclosing the side A, as shown in Fig. 1.

C is a thumb-lever, fulcrumed on the rivet c, 40 and extending outward, terminating in a button, D, and a similar lever, E, is also fulcrumed on the same rivet c, and is provided with a button, F, and each lever has a spring, a, which keeps them separated. 45

G are projecting teats—one on each lever—so that when the levers are compressed the teats will be below the outside of the case, which is then inserted in the key-hole of the lock, and the levers allowed to fly outward, so that the teats will project between the lock-plates, which effectually prevents the insertion of a key or pick from the outside.

H is a hole extending through the casing from side to side for the insertion of the end 55 of a cigar.

e are semicircular knife-edges on the levers C E, so that when they are compressed they will clip off the end of the cigar.

Having thus described my invention, what I 60 claim as new and useful, and desire to secure by Letters Patent, is—

1. The combination, with the casing A B, of the levers C E, provided with springs a a and projecting teats G G, as and for the purpose 65 set forth.

2. The combination, with the casing A B, having hole H, of the levers C E, each having a spring, a, cutting-edge e, and projecting teat G, as set forth. 70

In testimony whereof I affix my signature in presence of two witnesses.

GEORGE McGOVERN.
